US00D448772B1

(12) **United States Design Patent** (10) Patent No.: **US D448,772 S**
(45) Date of Patent: ** Oct. 2, 2001

(54) **ELEMENT OF AN ELECTRONIC COMPUTER**

(75) Inventors: **Yoshihiko Sugano**, Tokyo (JP); **Kenji Shimano**, Irvine, CA (US); **Shogo Suzuki**, Matsudo (JP); **Scott Yu**; **Thomas Keen**, both of San Francisco, CA (US)

(73) Assignee: **Kabushiki Kaisha Toshiba**, Kawasaki (JP)

(**) Term: **14 Years**

(21) Appl. No.: **29/125,626**

(22) Filed: **Jun. 28, 2000**

(51) LOC (7) Cl. **14-02**

(52) U.S. Cl. **D14/439**; D14/432

(58) Field of Search D14/345, 368, D14/341, 342, 432, 439, 455, 456; D8/323-329; 16/267, 285, 342, 354; 361/681, 683, 687, 755

(57) **CLAIM**

The ornamental design for an element of an electronic computer, as shown and described.

DESCRIPTION

FIG. 1 is a top, front and right side perspective view of an element of an electronic computer showing our new design, FIG. 2 is a front elevational view thereof, FIG. 3 is a right side elevational view thereof, FIG. 4 is a left side elevational view thereof, FIG. 5 is a rear elevational view thereof, FIG. 6 is a top plan view thereof, FIG. 7 is a bottom plan view thereof, FIG. 8 is a top plan view showing the article in a closed position thereof, FIG. 9 is a front elevational view showing the article in the closed position thereof; and, FIG. 10 is a right side elevational view showing the article in the closed position thereof. The broken line showing the remainder of the electronic computer is for illustrative purposes and forms no part of the claimed design.
